UNITED STATES PATENT OFFICE.

AUGUST REGAL, OF BANJALUKA, AUSTRIA-HUNGARY, ASSIGNOR OF ONE-THIRD TO FRANJO HARAZIM AND ONE-THIRD TO EUGEN KARAZEJ, OF BANJALUKA, AUSTRIA-HUNGARY.

PROCESS FOR WEAVING IN NATURAL COLORS WITHOUT PATTERN-CARDS.

No. 874,370.

Specification of Letters Patent.

Patented Dec. 17, 1907.

Application filed June 11, 1906. Serial No. 321,249.

To all whom it may concern:

Be it known that AUGUST REGAL, professor, a subject of the Emperor of Austria-Hungary, residing at Banjaluka, Bosnia, 5 Austria-Hungary, have invented certain new and useful Improvements in Processes for Weaving in Natural Colors Without Pattern-Cards; and he does hereby declare the following to be a full, clear, and exact 10 description of the invention, such as will enable others skilled in the art to which it appertains to make and use the same.

This invention relates to an application to the art of weaving of the process used in 15 three color printing, for the purpose of obtaining correct woven reproductions of natural objects or pictures. For this purpose first, negatives of the three single color partial pictures are prepared as in the three 20 color printing process by photographing the article to be reproduced, the said negatives being made in red (purple red) yellow and blue (green blue) by the use of light filters and from these negatives single color partial 25 positives are printed, by means of the well-known chromate process, on three plates made of insulating material (glass, porcelain, vulcanized rubber) and galvanically coated with metal. The portions of 30 the partial pictures which have not been exposed to light, are electrically conducting after the plates have been washed and slightly etched, the portions exposed to light remaining covered with chromium 35 oxid gelatin, that is to say non-conducting.

In the three-color printing process, the printing plates or blocks are covered by 40 means of rollers, with printing inks of the three fundamental colors, and the partial pictures printed on the top of each other, whereby a combined picture in natural colors is obtained, as the three fundamental colors, as is well known, are sufficient for reproducing any shades and gradations of 45 color to be found in pictures or in nature. A picture produced by the three color printing is constituted throughout by points, most of which show combined colors. They are those points in which the paints of two or 50 three fundamental colors coincide, which is generally called "color subtraction." To the naked eye, the multitude of colored points forms one harmonious whole, and by "color addition" produces the natural impression of the original from which the par-

tial photographs were taken. In the present invention according to which a picture is to be woven from threads the combination colors cannot be produced by color covering or subtraction as the threads are not transparent. But it is possible to arrange in the warp threads of combined colors, to employ these as well as threads of the fundamental colors and to allow them to act on the spectator by color addition alone, as in a printed 60 three-color picture. The points of the pictures produced by the three color printing process are replaced in the woven fabric by corresponding points of intersection and therefore the apparatus according to this invention is applied to a wire loom of well known construction.

In addition to the warp threads of the three fundamental colors, red, yellow and blue, there are also provided threads of 75 orange, violet, green (combinations of two colors), black and white (combinations of three colors) and a pile warp is used for each color, so that altogether, in addition to the ground warp, there are eight pile warps. In 80 accordance with the pile warps the hooks used in the loom are arranged in eight series, each of which contains as many hooks as there are pile warp threads to be woven into the fabric in the direction of its width, as 85 each of such pile warp threads is connected to one hook. From this series of threads, the proper pile warp thread is raised at given moments for forming the upper shed. The hooks are raised by means of narrow lifting 90 blades arranged on bars which are moved by a driving arm by means of a "receiver" or device operated by an electromagnet, the said bars remaining in the position corresponding to the extent of movement of the 95 driving arm, the extent of such movement being capable of being regulated by the receiver. In order to enable all the bars with their blades to be moved, the receiver with the driving arm is moved longitudinally in 100 front of the columns of hooks the driving arm returning again to its original position after every operation, before it acts on the next bars.

The action of the receiver is determined by 105 the "transmitter" of the device, which consists of the three already described plates arranged side by side in one frame, but electrically insulated from each other. On the first plate all those points act as conductors 110

which reproduce the portions of the total picture, which have been photographed with the green filter, on the second plate those which have been photographed with the 5 violet filter, and on the third plate, those which have been photographed with the orange filter, while the remaining portions of the plates are covered with chromium oxid gelatin, that is to say, are non conducting. On each of the plates slides a contact pin; the contact pins are provided with a common guide, but are electrically insulated from each other, and move synchronously with the receiver. Each of the three transmitter plates is connected to one pole of a source of current, the second pole of which is connected to the plate above which the receiver slides. The plate is made of insulating material and contains series of contacts 15 which are arranged in such a manner, that the columns of contacts lie in the plane of the columns of hooks. The source of current is connected to the second, fourth, sixth series of contacts, and the contact pins of the transmitter plates to the third, fifth and seventh series of contacts. When a contact of the 20 third series of contacts is connected by a bridge to an opposite contact of the fourth series, the source of current, in the event of 25 the contact pin switched into the circuit touching a conducting point of the corresponding transmitter plate, sends a current through the bridge. The same thing happens when the fourth and the fifth series of 30 contacts and the sixth and seventh series of contacts are connected together by a bridge and the corresponding contact pins touch the conducting points of the corresponding transmitter plates. The bridges are constituted by the electromagnets of the receiver, 35 which operate the latter with the driving arm, so that the blades should come under the corresponding hooks and raise them.

Assuming that the first contact pin is in 40 the center of the transmitter plate carrying the red partial photograph, then the second and third contact pins are in the center of the transmitter plates for the yellow and blue partial photographs. Only the following cases are possible, (1) the center of the 45 transmitter plate for the red partial photograph is conducting, and the central points of the two other plates are non-conducting. (2) the center of the second plate is conducting and that of the two other plates non-conducting. (3) the center of the third plate is conducting, and that of the two other non-conducting. (4) the center of the first and second plates are conducting, and that of the 50 third plate non-conducting. (5) the centers of the first and third plates are conducting, and that of the second non-conducting. (6) the centers of the second and third plates are conducting and that of the first non-conducting. (7) the centers of all the three plates

are conducting and (8) the centers of all the three plates are non-conducting.

If, for instance, we had the first case, which means that the center of the object or picture, the partial one-color photograph of 70 which in red is given on the first transmitter plate and which in three-color printing is rolled with red ink, then, in order to reproduce this point, a red binding point must be produced in the fabric, that is to say, a red 75 pile thread must be brought into the upper shed. Owing to the contact pin coming into contact with the conducting center the circuit into which the contact pin is switched in, will be closed. The current passes from 80 the course of current through the first transmitter plate into the first contact pin, passes through the windings of the electromagnet forming the bridge between the corresponding contact of the receiver plate and returns 85 to the source of current. In consequence of the attraction of the electro-magnet, the mechanism operating directly the driving arm, comes in action and drives the bar in front of it carrying the blade, forward until 90 the blade arrives under the hook with which is connected a red pile thread. The driving arm is then returned to its initial position, before the receiver arrives in front of the next column of hooks, so that the device is 95 ready for advancing the next bar.

If for instance, we should have the case mentioned under 5, in which the centers of the red and blue plates are conducting, that would mean, that the corresponding point of 100 the original reproduces red and blue points, that is to say, is violet. In three-color printing, such a violet point could be produced by the coincidence of red and blue colored points. In the present case, in which 105 the coincidence of colors or color subtraction cannot be utilized for which purpose violet threads are provided in the pile warp, a violet thread must be raised into the upper shed. Owing to the contact of the first and 110 third contact pins, the circuit is again closed, but it is now divided into two branches. One branch current will flow, like the whole current before, through the windings of the respective electromagnet the other into the 115 windings of a second electromagnet and back again to the source of current. Two electromagnets will therefore be simultaneously excited, whereby the movement of the driving arm will take place in such a way, that the 120 blade will be brought under a hook on which a violet upper pile warp thread is suspended, which will now be lifted into the upper shed.

In the case 7 all the three colors are operative. In three-color printing, a black point 125 will be obtained by the coincidence of the three colored points, but in this invention a black pile warp thread is raised. In the last case, in which no contact pin establishes a conducting connection, the circuit remains 130

broken and the electromagnets do not act. The bars remain in their normal position in which the blades are below the hooks of the first series to which are connected white pile 5 warp threads. During the formation of the upper shed, a white pile thread will then be raised.

Having now particularly described as ascertained the nature of our said invention 10 and in what manner the same is to be performed, we declare that what we claim is:

The process of weaving in natural colors without jacquard-cards which consists in preparing monochrome photographic negatives 15 from the original to be copied, preparing a positive from each negative and mak-

ing the part of each positive which was exposed to light electrically insulative and the part of each positive which was not exposed to light electrically conductive, and then 20 employing said positives, individually and in changing combinations with each other, as circuit-makers and -breakers in an electro-magnetic apparatus controlling the warp selecting and actuating devices in a loom, sub- 25 stantially as described.

In testimony whereof, he affixes signature, in presence of two witnesses.

AUGUST REGAL.

Witnesses:

HARRY BELMONT,
ALVESTO S. HOGUE.
